UNITED STATES PATENT OFFICE

154,113

DESIGN FOR AN INDICATOR CONTROL PANEL UNIT FOR STOVES

Edward A. Fink, Chicago, Ill.

Application December 29, 1947, Serial No. 143,427

Term of patent 14 years

(Cl. D81—25)

To all whom it may concern:

Be it known that I, Edward A. Fink, a citizen of the United States, residing at Chicago, in the county of Cook and State of Illinois, have invented a new, original, and ornamental Design for an Indicator Control Panel Unit for Stoves, of which the following is a specification, reference being had to the accompanying drawing, forming a part thereof.

Fig. 1 is a front elevational view of an indicator control panel unit for stoves, showing my new design;

Fig. 2 is a top plan view thereof;

Fig. 3 is an end elevational view; and

Fig. 4 is a cross-sectional view thereof taken on line 4—4 of Fig. 1.

The dominant features of my design reside in the portions shown in full lines.

I claim:

The ornamental design for an indicator control panel unit for stoves, as shown and described.

EDWARD A. FINK.
